UNITED STATES PATENT OFFICE.

CORNELIUS A. BECKER, OF WHITE SALMON, WASHINGTON.

GATE.

1,238,624.

Specification of Letters Patent. Patented Aug. 28, 1917.

Application filed February 21, 1917. Serial No. 150,187.

To all whom it may concern:

Be it known that I, CORNELIUS A. BECKER, a citizen of the United States, residing at White Salmon, in the county of Klickitat, State of Washington, have invented certain new and useful Improvements in Gates; and I do hereby declare the following to be a full, clear, and exact description of the invention, such as will enable others skilled in the art to which it appertains to make and use the same.

This invention relates to gate operating mechanism, and more particularly pertains to means for operating farm gates into open or closed position.

The object of the invention is to provide a simple and effective mechanism for swinging farm gates into open position from either side of the gateway without the necessity of the operator leaving his seat or saddle, the gate being as readily closed after the operator has passed through the gate.

More particularly, the object of my invention consists in the provision of means for simultaneously operating the members of a double gate into open or closed position, the gates being so intergeared that they may be swung with a minimum of labor and incident jar.

With the above objects in view and such others as may hereinafter appear, my invention will now be fully set forth and described, reference being had to the accompanying drawings:—

35 In the drawings:—

Figure 1 is a front elevation, one of the posts being broken away to show the gate operating mechanism.

Fig. 2 is a front elevation of one of the 40 gates in open position,

Fig. 3 is an end view, and

Fig. 4 is a perspective view of an operating track used in connection with the apparatus.

Referring more particularly to the drawings, 45 1 represents the gate posts, each of which is formed of a pair of spaced parallel uprights between which is preferably secured the cross bar 2 at a suitable overhead elevation. Pivotal secured between the 50 members of the posts 1 are the gates 3 of suitable and usual construction with the exception of the top short bars 4 which act as guides and braces for the guide bands 5 which are formed of angle-iron and are bolted upon opposite sides of the gates 3 in 55 coincident relation so that one flange thereof

extends outwardly from the sides of the gates. The gates are carried by studs 6 which operate in the bearings 7, the latter being located at a suitable height so as to 60 permit the gates to swing into vertical position between the uprights of the posts 1. Secured to the lower ends of the bands 5 upon one side of the gates 3 are the cables 8, which thence pass for a certain distance 65 over the curved portion of the bands and are passed through pulleys 9 which are secured to the inner sides of the posts 1 above the gates. From these pulleys the cables are passed to corresponding pulleys 11 upon 70 the upper ends of posts 12 positioned at suitable distances from the gateway upon opposite sides of the latter and also upon opposite sides of the driveway. Suitable weights 13 secured to the free ends of these 75 cables serve as handles for the operator to grasp in pulling the cables for opening the gates, it being obvious that by pulling the cables downwardly through the pulleys 11 causes the gates to be elevated by the operation of the cables 8 upon the bands 5. Secured to the rear ends of the bands 5, which are extended rearwardly to provide the brackets 14 are the ends of other cables 15 which are passed through the pulleys 16 80 also carried by the posts above the gates, but upon the outer sides of the former, after which the cables 15 are passed through pulleys 17 which are also carried by the posts 12 and are weighted as at 18, so that the 85 weights 18 counterbalance the weights of the cables 8. Thus when the weights are lowered, the cables 15 are consequently raised through the retraction of the cables 8, and vice versa, when the last mentioned 90 95 cables are operated to close the gates. Positioned between the uprights of the posts 1, in directly opposite positions, are the pulleys 19 which appear directly below corresponding pairs of pulleys 20 also located 100 between the uprights of the posts 1 in suitably spaced relation, brackets 21 being provided for their proper rotative mounting. Secured to the lower end of the second bands 5 upon each gate is a cable 22 which passes 105 thence around the bands 5 to the adjacent pulley 19 thence upwardly over the superimposed pulley 20 across the gateway just below the cross bar 2 over the opposite pulley 20, thence in front of and below the opposite pulley 19, after which its end is connected to 110 an eyelet 23 upon the opposite gate, the eye-

let 23 being preferably located on the rear upper corner of the gate. Thus, the cables 22 being similarly but reversely connected between the two gates are operative, when 5 one or the other gate is actuated to swing the second gate simultaneously and with a balanced action.

When it is desired to open the gate, either 10 of the cables 8 or the weights 13 is actuated thereby pulling up on the lower ends of the corresponding guide bands 5. This action tends to lift the gate, and by reason of the connecting cables 22 the gates are simultaneously thrown back to open position, as 15 indicated in Fig. 2. Obviously this action raises the weights 18, and projects the cables 15 rearwardly over the pulleys 16 and behind the post 1. In order to close the gates, 20 the weight 18 is now pulled downwardly, this action causing the cable 15 to pull upon the rear end 14 of the guideband 5 and lift the gates to their closed position.

From the foregoing it will be apparent 25 that I have provided a simple and easily actuated form of gate operating mechanism. The guide or track bands 5 which are duplicated upon opposite sides of each gate form of each gate a very rigid structure, aside 30 from their functions of properly guiding and positioning the cables 8 and 22. The gates are balanced for opening or closing,

Copies of this patent may be obtained for five cents each, by addressing the "Commissioner of Patents, Washington, D. C."

so that little power is needed for their actuation in either position, and they are equally simply connected for simultaneous balanced action when either one of the gates 35 are actuated into open or closed position.

What I claim as my invention is:—

The combination with gate posts, of gates pivoted between the posts to be swung into vertical position, arcuate cable guide bands 40 mounted upon opposite sides of each gate, and extending from the lower edge of the gate to the upper rear corner thereof, a cable connected to the lower end of one of the bands on each gate and carried over the 45 band to the corresponding post for lifting the gates, a cable connected to the upper rear end of each of the gates for actuating the gates into closed position, and a cable extending from the lower end of each one 50 of the second of the arcuate guide bands to the adjacent post and connected across the gate posts, and pulleys carrying the last mentioned cables whereby actuation of one of the gates causes the simultaneous and 55 similar action of the other gate.

In testimony whereof, I affix my signature in the presence of two witnesses.

CORNELIUS A. BECKER.
